UNITED STATES PATENT OFFICE.

ELIAS A. W. BEEMER, OF HAMILTON, ONTARIO, CANADA.

MONKEY-WRENCH.

1,113,948.

Specification of Letters Patent. Patented Oct. 20, 1914.

Application filed February 12, 1913, Serial No. 748,036. Renewed March 16, 1914. Serial No. 825,155.

To all whom it may concern:

Be it known that I, ELIAS A. W. BEEMER, of the city of Hamilton, in the Province of Ontario, Canada, have invented certain new and useful Improvements in Monkey-Wrenches, of which the following is a specification.

This invention relates to wrenches in which a fixed jaw is formed at one end of 10 a shank on which a movable jaw is adjustable usually by means of a worm or screw, and my object is to provide a wrench which will be as strong and reliable as the older type with the added advantage of quick 15 adjustment.

I attain my object by providing the movable jaw with a friction block adapted to engage a friction face on the shank, the friction block being forced into engagement 20 with said friction face by means of a toggle pivoted at one end in the movable jaw and at the other in the block, the whole being constructed in detail substantially as described and illustrated in the accompanying 25 drawings in which—

Figure 1 is a side elevation, partly broken away, of a wrench constructed in accordance with my invention. Fig. 2 is a side elevation of part of the wrench looking at 30 the other side. Fig. 3 is a cross-section through the movable jaw. Fig. 4 is a plan view, partly in section, of the toggle.

In the drawings like numerals of reference indicate corresponding parts in the different figures.

1 is the shank of the wrench at one end of which is formed a fixed jaw 2. The sliding jaw 3 is movable on the shank in the usual manner. The sliding jaw is, however, recessed to receive the friction block 4, which has one edge shaped to engage the friction face 5 formed longitudinally of the shank. This friction face is preferably beveled outwardly, as indicated in Figs. 2 and 3, so that if the friction block be pressed toward it the friction block will also be pushed into firm contact with the outer wall 6 of the recess in the sliding jaw. The friction face is also inclined from the back 45 toward the front of the wrench at the handle end of the shank, as shown in Fig. 1. The purpose of this will hereinafter appear.

The block 4 has a pin 7 connected therewith, which projects through the slot 8 formed in the wall 6 of the recess in the sliding jaw. The friction block 4 is pressed

toward the face 5 by means of a toggle 9. This has a bearing at one end on a pin 10 passing through the sliding jaw. The other end has a bearing in the block 4, this end being provided with the rounded portion 11 fitting into a suitably shaped recess in the block.

A bent spring 12 is coiled around in the recess 13 formed in the toggle about the pin 10, one end engaging the toggle and the other the movable jaw. This spring tends to move the toggle to cause the friction block 4 to engage the face 5. The operation of the wrench will be obvious. By pulling 70 down on the pin 10 the block 4 is disengaged from the friction face 5. The movable jaw may thus be freely slid up or down to the desired position. When the pin is released the spring throws up the toggle and engages the friction block with the face 5. The action of the spring may, of course, be aided by upward pressure on the pin.

The toggle lying very nearly in a perpendicular to the length of the friction face 5 exerts powerful pressure on the friction block so that the wrench will hold very firmly.

The lengthwise inclination of the friction face 5 increases the security of the grip for 85 a small opening of the jaws when any lost motion is particularly prejudicial, as with small openings the wrench is usually being employed on nuts with comparatively small faces.

From the above description it will be seen that I have devised a wrench which will satisfactorily accomplish the objects of my invention as set out in the preamble to this specification.

What I claim as my invention is:—

1. In a wrench the combination with the shank having a friction face formed longitudinally on one side of the shank facing toward the other edge of the same, of a sliding jaw movable on the shank and having a recess therein; a friction block in said recess adapted to engage the friction face; and a toggle pivoted at one end in the block and at the other end in the jaw.

2. In a wrench the combination with the shank having a friction face formed longitudinally on one side of the shank facing toward the other edge of the same, of a sliding jaw movable on the shank and having a recess therein; a friction block in said recess adapted to engage the friction face; a toggle

pivoted at one end in the block and at the other end in the jaw; and a spring engaging said toggle and the jaw tending to press the said block into engagement with the said face.

3. In a wrench the combination with the shank having a friction face formed longitudinally on one side of the shank facing toward the other edge of the same and outwardly beveled, of a sliding jaw movable on the shank and having a recess therein; a friction block in said recess adapted to engage the friction face; and a toggle pivoted at one end in the block and at the other end in the jaw.

4. In a wrench the combination with the shank having a friction face formed longitudinally on one side of the shank facing toward the other edge of the same and inclined from the back toward the front at the handle end of the shank, of a sliding jaw movable on the shank and having a recess therein; a friction block in said recess adapted to engage the friction face; and a toggle pivoted at one end in the block and at the other end in the jaw.

5. In a wrench the combination with the

shank having a friction face formed longitudinally on one side of the shank facing toward the other edge of the same outwardly beveled and inclined from the back toward the front at the handle end of the shank, of a sliding jaw movable on the shank and having a recess therein; a friction block in said recess adapted to engage the friction face; and a toggle pivoted at one end in the block and at the other end in the jaw.

6. In a wrench the combination with the shank having a friction face formed longitudinally on one side of the shank facing toward the other edge of the same, of a sliding jaw movable on the shank and having a recess therein bounded by a slotted outer wall; a friction block in said recess adapted to engage the friction face and provided with a pin projected through said slot; and a toggle pivoted at one end in the block and at the other end in the jaw.

Hamilton this 20th day of January, 1913.

ELIAS A. W. BEEMER.

Signed in the presence of—
GEO. ALLEN BEEMER,
RICHARD BUTLER.
